NECKTIE CLAMP

Filed April 30, 1926

WITNESS:

Gerald Hennessy

Patented Sept. 7, 1926.

UNITED STATES PATENT OFFICE.

GRAY T. LOYD, OF LYNCHBURG, VIRGINIA.

NECKTIE CLAMP.

Application filed April 30, 1926. Serial No. 105,814.

My present invention has reference to a simple means for clasping a necktie to a shirt or like garment, and my object is the provision of a tie clasp that may be cheaply constructed and marketed at a fair selling price, and which shall be thoroughly efficient for its purpose.

A still further object is the provision of a tie clasp that includes a body plate that may be highly ornamented and which has secured on its inner face one element of a spring plate, the said plate having its opposite end rounded to provide an inner spring jaw for cooperation with the plate, the mouth between the jaw and plate being flared so that the device may be readily inserted on a tie and on the garment to which the tie is to be clasped, while the inner face of the plate, and if desired, the spring jaw may be roughened for more effective clamping engagement with the tie and with the garment.

To the attainment of the above broadly stated objects and others which will appear as the nature of the invention is better understood, the invention resides in the improvement as hereinafter described and definitely claimed.

In the drawings:

Figure 1 is a perspective view illustrating the application of my improvement.

Figure 2 is a side elevation of the improvement.

Figure 3 is a bottom perspective view thereof.

Figure 4 is an approximately central longitudinal sectional view through the improvement.

Figure 5 is a transverse sectional view approximately on the line 5—5 of Figure 2.

Figure 6 is a bottom plan view of a slight modification.

Figure 7 is a similar view of a still further modification.

The body plate of the improvement, indicated by the numeral 1, may be of precious or inferior metal, and may be constructed of any other desired material. The plate preferably has its outer face ornamented.

In the showing of Figures 1 to 6 of the drawings, the plate 1 has both its ends and edges flanged, as at 2, thereby providing the inner face of the plate with what may be termed a pocket. Also these edges may be rounded inwardly and secured to the edges and arranged in what I have termed the

pocket of the plate, there is a strip 3 of any suitable or desired material. Preferably the strip has an outer abrasive face, as indicated by the numeral 4, and let in the pocket and covered by the strip there is the U-shaped body portion of a continuous spring wire member. The body portion of the wire member is indicated by the numeral 5, and the legs thereof pass through the sheet 3 at one of the edges of the said sheet and from thence the legs of the body 5 are rounded inwardly, as at 6, and continued to provide the same with parallel arms 7. The outer ends of the arms 7 are rounded upon themselves in the direction of the plate 1, as indicated by the numerals 8, and these rounded portions are continued to provide the parallel arms 9 of the jaw 10 of the improvement. The arms providing the jaw 10 are preferably roughened or serrated, as at 11, and the entrance passage or mouth between the jaw or the plate is flared, so that the device may be readily inserted over the edge of a necktie 12 and over the front seam 13 of a shirt or like garment 14, as disclosed by Figure 5 of the drawings.

In Figure 6 the plate 1' is similar to that above described and as a matter-of-fact, the spring jaw is also similarly constructed. In this instance, however, the parallel arms 15 and the U-shaped base of the endless spring wire are soldered to or otherwise secured to the inner face of the base 1'. Also these arms are roughened or serrated, as at 16. The ends of the arms are rounded outwardly to provide outer arms 17 which are inwardly inclined and which have their ends rounded downwardly toward the plate 1', as at 18. From the rounded portions the wire is continued to provide the parallel arms 19 of the U-shaped jaw. The outer end of the jaw which, of course, is disposed between the arms 16 and which is adapted for frictional engagement with the inner face of the plate 1', has arranged thereon and secured thereto an abrasive sheet 20. As in the construction above described there is a flared entrance between the jaw and the plate.

In Figure 7 the body plate 21 has secured on its inner face the flat inner arm 22 of a spring plate. The plate is rounded outwardly and inwardly, as at 23, and from thence continued to provide the outer arm 24 of the device. The arm 24 has its end

rounded, as at 25, toward the plate 21 and is from thence continued to form the jaw 26 which cooperates with the body 22 of the plate.

It is believed that when the foregoing description has been carefully read in connection with the accompanying drawings, the simplicity of my construction, the cheapness at which the same may be manufactured and marketed and the thorough efficiency of the device will be perfectly apparent to those skilled in the art to which the invention relates but it is to be understood that I do not wish to be restricted to the precise details of construction herein set forth and hold myself entitled to make such changes therefrom as fairly fall within the scope of what I claim.

Having described the invention, I claim:—

1. A necktie holder, including a body plate whose edges and ends are flanged inwardly, a spring member having an arm

arranged between the flanges, said member having its end rounded and continued over 25 the plate to provide an outer arm, said outer arm being rounded inwardly in the direction of the plate and from thence continued over the plate to provide a spring jaw, and an abrasive sheet between the jaw 30 and the plate.

2. A necktie holder, including a body plate whose edges and ends are flanged inwardly, a spring member having an arm 35 arranged between the flanges, said member having its end rounded and continued over the plate to provide an outer arm, said outer arm being rounded inwardly in the direction of the plate and from thence continued over the plate to provide a spring 40 jaw, an abrasive sheet between the jaw and the plate, and an abrasive facing for the jaw.

In testimony whereof I affix my signature.

GRAY T. LOYD.
